US00D920176S

(12) **United States Design Patent** (10) **Patent No.:** **US D920,176 S**
(45) **Date of Patent:** **** May 25, 2021**

(54) **GRILLE FOR A VEHICLE**

(71) Applicants: **Warner Science Applications Corp.,**
Ontario, CA (US); **Paramount**
Automotive Restyling Inc., Ontario,
CA (US)

(72) Inventor: **Mingfa Yang**, Calabasas, CA (US)

(73) Assignees: **Warner Science Applications Corp.,**
Ontario, CA (US); **Paramount**
Automotive Restyling Inc., Ontario,
CA (US)

(**) Term: **15 Years**

(21) Appl. No.: **29/673,544**

(22) Filed: **Dec. 14, 2018**

Related U.S. Application Data

(62) Division of application No. 29/602,711, filed on May 2, 2017, now Pat. No. Des. 836,042.

(57) **CLAIM**

The ornamental design for a grille for a vehicle, as shown and described.

DESCRIPTION

FIG. 1 is a front, bottom and right side perspective view of a grille showing an embodiment of my new design;

FIG. 2 is a front elevational view thereof;

FIG. 3 is a left side elevational view thereof;

FIG. 4 is a right side elevational view thereof; and,

FIG. 5 is a top plan view thereof.

The broken lines showing mounting features for the grille are included for the purpose of illustrating environmental structures, and form no part of the claimed design.

1 Claim, 5 Drawing Sheets
